(57) **CLAIM**

The ornamental design for an electric self propelled motorized suitcase, as shown and described.

DESCRIPTION

FIG. 1 is a front view of an electric self propelled motorized suitcase showing the new design in which the handle and a bracket are both closed;

FIG. 2 is a back view of the electric self propelled motorized suitcase in which the handle and the bracket are both closed; FIG. 3 is a right view of the electric self propelled motorized suitcase in which the handle and the bracket are both closed; FIG. 4 is a left view of the electric self propelled motorized suitcase in which the handle and the bracket are both closed; FIG. 5 is a top view of the electric self propelled motorized suitcase in which the handle and the bracket are both closed; FIG. 6 is a bottom view of the electric self propelled motorized suitcase in which the handle and the bracket are both closed;

FIG. 7 is a front perspective view of the electric self propelled motorized suitcase in which the handle and the bracket are both closed;

FIG. 8 is a back perspective view of the electric self propelled motorized suitcase in which handle and the bracket are both closed;

FIG. 9 is a front view of an electric self propelled motorized suitcase in which the handle is closed and the bracket is open;

FIG. 10 is a back view of the electric self propelled motorized suitcase in which the handle is closed and the bracket is open;

FIG. 11 is a right view of the electric self propelled motorized suitcase in which the handle is closed and the bracket is open;

FIG. 12 is a left view of the electric self propelled motorized suitcase in which the handle is closed and the bracket is open;

FIG. 13 is a top view of the electric self propelled motorized suitcase in which the handle is closed and the bracket is open;

FIG. 14 is a bottom view of the electric self propelled motorized suitcase in which the handle is closed and the bracket is open;

FIG. 15 is a front perspective view of the electric self propelled motorized suitcase in which the handle is closed and the bracket is open;

FIG. 16 is a back perspective view of the electric self propelled motorized suitcase in which the handle is closed and the bracket is open;

(Continued)

FIG. 17 is a front view of an electric self propelled motorized suitcase in which the handle is open and the bracket is open in a special folding state;

FIG. 18 is a back view of the electric self propelled motorized suitcase in which the handle is open and the bracket is open in a special folding state;

FIG. 19 is a right view of the electric self propelled motorized suitcase in which the handle is open and the bracket is open in a special folding state;

FIG. 20 is a left view of the electric self propelled motorized suitcase in which the handle is open and the bracket is open in a special folding state;

FIG. 21 is a top view of the electric self propelled motorized suitcase in which the handle is open and the bracket is open in a special folding state;

FIG. 22 is a bottom view of the electric self propelled motorized suitcase in which the handle is open and the bracket is open in a special folding state;

FIG. 23 is a front perspective view of the electric self propelled motorized suitcase in which the handle is open and the bracket is open in a special folding state;

FIG. 24 is a back perspective view of the electric self propelled motorized suitcase in which the handle is open and the bracket is open in a special folding state;

FIG. 25 is a front view of an electric self propelled motorized suitcase showing the handle and the bracket both open;

FIG. 26 is a back view of the electric self propelled motorized suitcase in which the handle and the bracket are both open;

FIG. 27 is a right view of the electric self propelled motorized suitcase in which the handle and the bracket are both open;

FIG. 28 is a left view of the electric self propelled motorized suitcase in which the handle and the bracket are both open;

FIG. 29 is a top view of the electric self propelled motorized suitcase in which the handle and the bracket are both open;

FIG. 30 is a bottom view of the electric self propelled motorized suitcase in which the handle and the bracket are both open;

FIG. 31 is a front perspective view of the electric self propelled motorized suitcase in which the handle and the bracket are both open;

FIG. 32 is a back perspective view of the electric self propelled motorized suitcase in which the handle and the bracket are both open;

FIG. 33 is a front view of an electric self propelled motorized suitcase showing in which the handle is open and the bracket is closed;

FIG. 34 is a back view of the electric self propelled motorized suitcase in which the handle is open and the bracket is closed;

FIG. 35 is a right view of the electric self propelled motorized suitcase in which the handle is open and the bracket is closed;

FIG. 36 is a left view of the electric self propelled motorized suitcase in which the handle is open and the bracket is closed;

FIG. 37 is a top view of the electric self propelled motorized suitcase in which the handle is open and the bracket is closed;

FIG. 38 is a bottom view of the electric self propelled motorized suitcase in which the handle is open and the bracket is closed;

FIG. 39 is a front perspective view of the electric self propelled motorized suitcase in which the handle is open and the bracket is closed; and,

FIG. 40 is a back perspective view of the electric self propelled motorized suitcase in which the handle is open and the bracket is closed.
